UNITED STATES PATENT OFFICE

DAVID E. BRANSON, OF RIVER EDGE, NEW JERSEY, ASSIGNOR TO AMERICAN TELEPHONE AND TELEGRAPH COMPANY, A CORPORATION OF NEW YORK

TELEGRAPH-MONITORING SYSTEM

Application filed December 16, 1927. Serial No. 240,478.

This invention relates to telegraph systems and more particularly to improved monitoring arrangements for use with the repeater apparatus of such systems.

5 An office at the terminal of a telegraph system will include racks which will hold a plurality of terminal repeaters. It has been the practice in the past to provide each of these repeaters with individual monitoring equipment, whereby an attendant may send 10 or receive signals through the repeater or make desirable current measurements therein. It is the primary purpose of the arrangements of this invention to provide a monitoring arrangement which may be common to a plurality of repeaters at a terminal office. Such an arrangement of common monitoring would have great advantages over a system 15 of individual monitoring in respect to a large saving in equipment. Other features and advantages of the invention will appear more 20 fully from the detailed description hereinafter given.

The invention may be more fully understood from the following description together with the accompanying drawing in the Figures 1 and 2 of which the invention is illustrated. Fig. 1 is a circuit diagram of a metallic terminal telegraph repeater. In 25 Fig. 2 is shown a circuit diagram of a common monitoring set which may be utilized with the terminal repeater of Fig. 1.

In Fig. 1 is shown the circuit of a terminal metallic repeater of the balanced loop type. The repeater includes the line L and the line 30 receiving relay 1, the sending relays 3, the break relay 2, the switching keys K₁, K₂, K₃ and K₄ and in addition connections to the noise killer device 4 and the balancing network N_L. It also includes a number of sending and receiving batteries to be described later and the line balancing jacks J₁ and the jacks J₂ and J₃ whereby 35 connections may be established with the monitoring set. The circuit of the monitoring set of Fig. 2 includes jacks J₄ and J₅. It also includes the loop meter shunts 5 and 6 and the meter 7. There is also shown a 40 telegraph sending key 8 connected to a local sending relay 9, a line sounder 10 and a

loop sounder 11. There are provided four switching keys K₅, K₆, K₇ and K₈ incidental to the operation of the monitoring set. As has been pointed out connections are made between the monitoring set and repeater by 45 means of cords and plugs and the jacks J₂, J₃, J₄ and J₅.

The invention may be more fully understood from the following description of its 50 operation.

Signals coming in over line L will operate the receiving relay 1 which will operate its armature to close a circuit through the sounder in the subscriber's loop and also through the line sounder 10 in the monitoring set. For this purpose key K₁ will be thrown up, key K₆ left normal and key K₃ thrown down. The circuits may be traced as follows: from battery 21, upper right hand contact of key K₁, conductor 22, contact of 55 relay 1, conductor 23, contact of key K₂, conductor 24, conductor 25, tip contacts of jacks J₃ and J₅, conductors 26 and 27, upper right hand contact of key K₆, conductor 28, through 60 line sounder 10, upper left hand contact of key K₆, over conductor 29 to ground. This circuit will control the operation of the sounder 10 in the monitoring set. The above traced circuit may be extended as follows: from conductor 26, through the line meter 65 shunt 6, conductor 35, contact of key K₈, conductor 34, sleeve contacts of jacks J₅ and J₃, conductor 33, upper right hand contact of key K₂, conductor 32, left hand contact of key K₃, and thence over the subscriber's receiving loop 31 to battery 30. This circuit 70 will operate the sounder in the subscriber's loop 31.

With the above described circuits closed a 75 reading may be taken by meter shunt 6 and meter 7 when key K₇ is operated down. This reading will give a measurement of the receiving loop current.

To measure the bias of the received or 80 incoming signals the keys K₈ and K₇ would be thrown down. The above traced circuit from the armature of the receiving relay 1 would be completed from conductor 26 as follows: meter shunt 6, conductor 35, conductor 85 37, contact of key K₇, conductor 38, and right 90 100 contact of key K₈.

hand contact of key K_8 , to ground through resistance 80. Under the above conditions a reading of meter 7 and meter shunt 6 will indicate the bias of the received signals.

- 5 When the subscriber wishes to send signals he will operate the key 40 in his sending loop 41. The key K_2 may be in normal position and key K_4 will be up. This will complete the following circuit: from battery 39, key 10 40, loop 41, left hand contacts of key K_2 , conductor 42, conductor 43, then over conductor 44 and through windings of sending relays 3 and break relay 2, conductor 46, contact of key K_3 , conductor 24, contact of key K_2 , conductor 23, armature of relay 1, conductor 22, contact of key K_1 , to battery 21. This will 15 operate the sending relay 3 and by means of conductors 47 and 48 will connect the sending batteries 49 and 50 to the conductors 51 and 52, the conductors 53 and 54, and thence to the sides of line L to transmit signals thereover. At the same time current may be transmitted over a circuit in parallel with conductors 51 and 52. This circuit comprises 20 conductors 60 and 61, ring contacts of jacks J_2 , J_3 , J_4 and J_5 , winding of loop sounder 11 and conductor 62. Accordingly the transmitted signals will be heard on the monitoring set by the loop sounder 11.
- 25 30 To measure the bias in the transmitted signals the key K_7 will be left in normal position. The above traced circuit to loop sounder 11 may be extended by a shunt or leak circuit comprising conductors 63 and 64, contacts of key K_7 and loop meter 7. The loop meter 7 will then indicate the bias in the transmitted signals.

The key K_2 is termed the cutting key. When it is in normal position the received 40 signals will pass through the repeater both to the subscriber's loop and to the sounder in the monitoring set as has been pointed out heretofore. The sending loop is connected to the repeater so that signals originating in that 45 loop will be repeated to line "L". When the cutting key K_2 is thrown to a downward position the loops are cut off from the repeater and the monitoring arrangements may be used for 50 communication with the line. Under this condition it is still possible for the subscriber to send signals in the loop locally without being transmitted to the line "L".

When the cutting key K_2 is thrown to its 55 upward position it opens the conductors 51 and 52, and hence disconnects the sending relay armatures from the line L, thereby preventing signals from being transmitted to the line L from the loop. Signals will be recorded to the loop sounder 11 under this condition. Also the receiving relay circuit and conductor 23 will be opened at key K_2 to prevent signals from the line going to the subscriber.

60 The process of sending from the monitoring set is as follows: Signals are sent from the

monitoring set by opening and closing the loop circuit by means of the contacts of relay 9, which is operated from battery by means of key 8. This opening and closing of the loops when opposing batteries are connected there- 70 to will cause the subscriber's relays to operate and also cause the sending relays 3 to operate and send signals to the line L.

75 While the invention has been disclosed as embodied in certain specific arrangements which are deemed desirable, it is understood that it is capable of embodiment in many and other widely varied forms without departing from the spirit of the invention as defined by the appended claims.

80 What is claimed is:

1. A telegraph station comprising a plurality of repeater sets of the terminal type, each of said repeater sets including individual transmitting circuits and individual receiving 85 circuits, a single monitoring set common to a plurality of repeater sets, and switching means whereby each of said transmitting circuits and receiving circuits may be individually extended into said common monitoring set. 90

3. A telegraph station including a repeater set of the terminal type, said repeater set having a transmitting circuit and a receiving circuit, a monitoring set, switching means in said repeater set and said monitoring set whereby 95 said transmitting circuit and said receiving circuit may be extended into said monitoring set, and signal responsive means in said circuits as extended into said monitoring set.

3. A telegraph station including a repeater set of the terminal type, said repeater set having a transmitting circuit and a receiving circuit, a monitoring set, switching means in said repeater set and said monitoring set whereby 100 said transmitting circuit and said receiving circuit may be extended into said monitoring set, signal responsive means and current measuring devices in said monitoring set, and switching means in said monitoring set whereby 105 said signal responsive means and said current measuring devices may be selectively associated with said circuits as extended therein.

4. A telegraph station including a repeater set of the terminal type, said repeater set having a transmitting circuit and a receiving circuit, transmitting means in said transmitting circuit, a monitoring set, switching means in said repeater set and said monitoring set whereby 110 said transmitting circuit and said receiving circuit may be extended into said monitoring set, signal responsive means and current measuring devices in said monitoring set, and switching means in said monitoring set whereby 115 said signal responsive means and said current measuring devices may be selectively associated with said circuits as extended therein.

5. A telegraph station including a repeater set of the terminal type, said repeater set having a transmitting circuit and a receiving circuit, and a monitoring set, said repeater set and said monitoring set each including switching 125 means and a set of six conductors whereby said transmitting circuit and said receiv- 130

ing circuit may be individually extended into said monitoring set.

6. A telegraph station including a repeater set of the terminal type, said repeater set having a transmitting circuit and a receiving circuit, a line circuit, a cutting key whereby said circuits may be selectively associated with said line circuit, a monitoring set, and switching means whereby said transmitting and receiving circuits may be individually extended into said monitoring set.

In testimony whereof, I have signed my name to this specification this 16th day of December, 1927.

15 DAVID E. BRANSON.
